UNITED STATES PATENT OFFICE.

LEWIS LEFKOWITZ, OF DANVILLE, VIRGINIA.

BOBBIN CONTROL.

1,302,936.

Specification of Letters Patent.

Patented May 6, 1919.

Application filed February 27, 1918. Serial No. 219,473.

To all whom it may concern:

Be it known that I, LEWIS LEFKOWITZ, a citizen of the United States, residing at Danville, in the county of Pittsylvania and State of Virginia, have invented a new and useful Bobbin Control, of which the following is a specification.

The subject of this invention is a bobbin control intended for use, primarily, on leather stitching machines.

In stitching leather it is desirable that the thread be waxed, and it is necessary that the thread be used before the thread becomes set or hardens and, for this reason it is not possible to wind a bobbin and hold it in reserve to be placed in the shuttle when the one in the shuttle becomes exhausted. As a consequence it becomes necessary to stop sewing on the machine when the bobbin is exhausted and rewind the bobbin. This naturally causes a loss of time and retards the turning out of finished work.

The device forming the subject matter of the present invention has been designed for the purpose of overcoming these difficulties.

It is also within the objects of the invention to provide means for stopping the winding of the bobbin when the same has become filled.

A further object within the contemplation of the invention is the provision of means for retaining the bobbin in a properly heated condition.

The invention also contemplates the provision of means for locking the bobbin against rotation with respect to the spindle.

A still further object within the contemplation of the invention is the production of a simple, durable and efficient bobbin control.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawing, wherein:

Figure 1 is a view in elevation, partly in section, of a bobbin control constructed in accordance with the invention, a fragment

of the machine to which it is attached being shown;

Fig. 2 is a view in side elevation of the device, the door of the housing opened and parts in section;

Fig. 3 is an enlarged detail sectional view substantially on the line 3-3 of Fig. 2.

Referring to the drawing by numerals of reference:

A usual supporting arm or bar 1 forming part of a leather stitching machine is illustrated and this bar merges, at one end, into a yoke the prongs of which form a bearing for a spindle 2. The spindle 2 is usually formed with a collar and a reduced end for the reception of the bobbin, the reduced end being threaded to receive a wing nut (not shown) by which the bobbin is clamped against the collar and so held in place.

In carrying out the invention, the collar 4 is beveled about its periphery at that face which is contacted by the bobbin, and the threaded end of the reduced end 5 is unnecessary. A bobbin 6 is mounted on the reduced end 5 and is held against rotation thereon by a pin 4' which extends from the face of the collar 4 and enters an aperture formed in the flange of the bobbin for its reception.

Secured to that prong of the yoke of arm 1 adjacent the collar 4 is a leaf spring 7 which extends downwardly beside the collar. A screw 8 is threaded into an extension 1' of the arm 1 and pivotally supports a cylindrical member or hub 9 from which extends a curved cam arm 10 adapted to contact the spring 7 so that the spring may throw the cam arm and hub when the parts have attained a predetermined position.

An arm 11 also extends from the hub and is positioned to enter edgewise between the flange of the bobbin 6 and the collar 4 so as to force the bobbin off the pin 4' and so release it from rotation with the spindle.

The hub 9 is also formed with an elongated flat arm 12 which is adapted to contact the bobbin at that portion between the flanges and upon which the thread 13 is wound. The thread 13 is led in the usual manner from the supply spool and through the wax pot (not shown) and the thread is smoothly distributed on the bobbin 6 because of the contacting arm 12 which is yieldingly held against the thread by the spring 7 and cam arm 10.

It will be readily apparent that, as the

bobbin fills with thread, the arm 12 is forced outwardly until the cam 10 passes the point on the spring 7 at which the spring ceases to force the cam inwardly, when the spring 5 will flex to throw the cam outwardly and release the arm 12 from contact with the thread 13 and force the arm 11 between the bobbin and collar and release the bobbin from the pin 4'.

10 That the wax through which the thread 13 has been drawn on its way to the bobbin may be kept in a proper liquid condition to permit suitable flexibility or pliability of the thread, a housing or boxing 14 is secured 15 on the arm 1 by screws (not shown) or otherwise. This housing incloses the reduced end of the spindle 2 and the bobbin and is provided with an aperture in its bottom or floor through which the thread 13 passes. This housing is provided with an 20 opening through which access may be had to the interior for the purpose of removing the bobbin from the spindle or placing it thereon, and this opening is normally closed 25 by a door 15 which is hinged to the housing and held in closed position by a catch 16 or the like.

10 A heating element in the form of a compartment or chamber 17 is provided in the 30 housing and an inlet pipe 18 communicates with the chamber 17 for the purpose of conducting steam from the regular heating system of the machine to the chamber. This

small quantity of steam is sufficient to maintain the wax in a pliable condition.

35 While stem has been set forth as the heating means because of the fact that machines of this character are usually heated by steam, it is to be understood that any other heat producing substance may be used.

40 It is thought that the operation of the device will be amply understood from the foregoing description without a special extended explanation thereof.

45 Having thus described the invention, what is claimed as new and sought by Letters Patent, is:—

50 A bobbin control, including a spindle, a bobbin adapted to be mounted on the spindle to rotate therewith, a hub pivotally mounted adjacent the spindle, a bobbin releasing blade extending from the hub, a thread distributing member extending from the hub, and means for holding the thread distributing member in contact with the 55 bobbin and throwing the bobbin releasing member to release the bobbin when the thread distributing member has moved a predetermined distance in one direction.

55 In testimony that I claim the foregoing as my own, I have hereto affixed my signature in the presence of two witnesses.

LEWIS LEFKOWITZ.
